UNITED STATES PATENT OFFICE

152,567

DESIGN FOR A TOY BANK

Donald D. Rupe, Des Moines, Iowa

Application November 19, 1947, Serial No. 142,621

Term of patent 3½ years

(Cl. D34—11)

To all whom it may concern:

Be it known that I, Donald D. Rupe, a citizen of the United States, residing at Des Moines, in the county of Polk and State of Iowa, have invented a new, original, and ornamental Design for a Toy Bank, of which the following is a specification, reference being had to the accompanying drawing, forming a part thereof.

Fig. 1 is a perspective view, Fig. 2 is a side view, and Fig. 3 is a back view of a toy bank, showing my new design.

I claim:

The ornamental design for a toy bank, substantially as shown.

DONALD D. RUPE.
